UNITED STATES PATENT OFFICE

2,208,226

LOOSE LEAF BINDER

William Nelson, Chicago, Ill., assignor to Wilson-Jones Company, Chicago, Ill., a corporation of Massachusetts

Application January 29, 1938, Serial No. 187,647

8 Claims. (Cl. 129—12)

This invention relates to a loose leaf binder of the type commonly called post binders, and refers particularly to the mechanism for actuating the post locking mechanism.

It is an object of this invention to provide simple and efficient means for locking the top cover of a post binder to the sheet retaining posts projecting upwardly from the bottom portion of the binder. It is a further object of this invention to provide means for holding the locking means in locked or open position so that both hands of the user are free to manipulate the binder and contents. Other objects of this invention will become apparent upon reading the following description, taken in conjunction with the accompanying drawings, in which:

Figure 1 is a fragmentary perspective view of a loose leaf binder embodying the invention;

Figure 2 is a perspective detail view of the post locking mechanism and actuating mechanism therefor in disassembled position;

Figure 3 is a top plan view of the upper clamping member with the top of the tubular housing removed showing the post locking mechanism in locking position;

Figure 4 is a cross-sectional view taken along the line IV—IV of Figure 3;

Figure 5 is a view similar to Figure 3 showing the post locking mechanism in open position;

Figure 6 is a cross-sectional view taken along the line VI—VI of Figure 5;

Figure 7 is a view similar to Figure 5 showing another embodiment of the invention;

Figure 8 is a cross-sectional view taken along the line VIII—VIII of Figure 7; and

Figure 9 is a view similar to Figure 2 showing the embodiment of Figures 7 and 8.

In the drawings, the reference numeral 2 indicates a cover member to which a post carrying member 3 is hingedly connected. A plurality of sheet retaining posts 4 may be permanently fixed to the member 3, or may screw into sockets provided in said post carrying member. A plurality of sheets 5 may be impaled upon the posts 4. The top cover member 6 is provided with a clamping member 7 connected thereto by means of hinge lugs 8.

The clamping member 7 comprises a tubular housing having its upper and lower walls apertured, as indicated at 9, and provided with end caps or plugs 10, 11, closing opposite ends of the tubular housing. It is obvious that the post carrying member may also be in the form of a tubular housing with similar end closures. The tubular housing of member 7 is provided with an

open top box 12 rigidly secured thereto a short distance from each pair of apertures 9.

The box 12 has one wall 13 recessed to form a projection 14 thereon. A locking lever 15 is provided with a tail portion 16 apertured, as indicated at 17, to receive the projection 14 therein. The locking lever is fulcrumed on the wall 13 and the engagement of the projection 14 and aperture 17 prevents displacement of the locking lever. A coiled spring 18 contained in the box 12 exerts constant pressure against the tail portion 16 to urge the locking lever towards locking position. The lever 15 is provided with an aperture 19 of a size sufficient to permit free movement of the housing 7 on the posts 4 when the lever 15 is parallel to the top wall of the housing, but small enough to bind against the posts 4 and prevent upward movement of the housing when the lever is at an angle to the parallel walls of the housing.

A slide member 20 is positioned in the tubular housing 7. One end of the slide member is bifurcated to provide a pair of projecting tines 21 spaced apart far enough for a box 12 to rest between them. A locking lever 15 has one end resting on the tines 21. The tines 21 are inclined, as indicated at 22, so that sliding movement of the member 20 will cause the end of the locking lever 15 to be raised until the locking lever is parallel to the top wall of the tubular housing.

The opposite end of the slide member 20 is provided with a rectangular aperture 23 in which another box 12 is positioned. A locking lever 15 has one end resting on the strips 24 formed by dieing out the aperture 23. The strips 24 are provided with an inclined surface 25 corresponding to the inclines 22. The end of the sliding member 20 beyond the aperture 23 is bent to form a shoulder 26.

A link 27 provided with an upstanding flange 28 abutting the shoulder 26 is secured to the slide member 20 by means of a pair of hooks 29 extending from the flange 28 over the top of the shoulder 26. It will be understood that the link 27 may be formed integral with the sliding member 20, but I prefer to form it as a separate member for manufacturing economy. The end of the link 27 opposite the shoulder 28 is offset, as indicated at 30 and is provided with a diagonally extending slot 31.

The end cap 10 is slotted, as indicated at 32, and an operating lever 33 is pivoted therein, as indicated at 34. One end of the lever 33 projects on the outside of the end cap and is provided with a suitable enlargement 35 to facilitate manipulation of the lever. The inner end of the lever 33

is connected to the link 27 by means of a stud 36 passing through the slot 31. A tension spring 37 has one end secured to the end cap, as indicated at 38, and the other end secured to a projection 39 extending upwardly from the flange 28.

The spring 37 exerts a constant force on the link 27 urging the link, and consequently the slide member 20, toward the end cap 10 so as to permit springs 18 to retain the locking mechanism in post locking position. When the lever 33 is operated to move the post locking mechanism to open position the end of the lever 33 connected to the link 27 is moved past the dead center 34 and the tension of the spring 37 retains the releasing mechanism in operative position, wherein the surfaces 22 and 25 in turn retain the post locking mechanism in open position.

The embodiment of the invention illustrated in Figures 7, 8 and 9 differs from the one previously described only in the slide and means for moving the slide. Accordingly, the description of the other mechanism will not be repeated.

In this embodiment the slide member 40 is similar to the slide member 20 but is provided with a raised portion 41 between the aperture 23 and the tines 21. The raised portion 41 is apertured, as indicated at 42, and is provided with a tongue 43 extending longitudinally of the aperture. The tongue 43 is almost the same length as the aperture 42, but a small space is allowed to permit a compression spring 44 to be impaled on the tongue. A box member 45 is secured to the lower wall of the tubular housing by any suitable means to provide an abutment for one end of the spring to press against. The box member 45 is designed to fit in the aperture 42 and straddle the tongue 43. The spring 44 exerts constant force against the slide member 40 urging it toward inoperative position.

An operating lever 46 pivoted in the slotted end cap 10 is provided at one end with a finger piece 47 to facilitate manipulation of the lever, and at the other end with a roller 48 adapted to abut the flange 26 of the slide member 40. In movement of slide member 40 from inoperative to post releasing position the roller 48 is moved from one side of the dead center to the other so that the spring 44 is effective to retain the releasing mechanism in either operative or inoperative position.

Although I have described two preferred embodiments of my invention in detail it will be understood that the description thereof is illustrative, rather than restrictive, as many details of the structure may be modified or changed without departing from the spirit or scope of the invention. Accordingly, I do not desire to be restricted to the exact construction described, except as limited by the appended claims.

I claim:

1. In a loose leaf binder, a tubular housing, a slotted end cap closing one end of said housing, a lever pivoted adjacent said end of said housing and having a finger piece projecting through said

slot, and post locking mechanism within said housing and releasable by said lever.

2. In a loose leaf binder, a tubular housing, an end cap closing one end of said housing, post locking mechanism in said housing, a slide member engaging said locking mechanism, and a lever secured to said end cap and pivoted to swing transversely of said housing to impart longitudinal movement to said slide member. 5

3. In a loose leaf binder, a tubular housing, 10 post locking mechanism in said housing, a slide member operable to move said locking mechanism from locking to open position, a lever provided with a roller abutting one end of said slide member, and spring means to maintain said slide 15 member in engagement with said rollers.

4. In a loose leaf binder, a tubular housing, a slotted end cap closing one end of said housing, locking mechanism in said housing, a slide member engaging said locking mechanism, a link 20 engaging said slide member, said link having a diagonally extending slot, and a lever projecting through said slotted end cap, said lever engaging said diagonal slot whereby movement of said lever is transmitted to said locking mechanism. 25

5. In a loose leaf binder, a tubular housing, a locking lever in said tubular housing, a slide member operable to move said locking lever from locking to open position, a link connected to said slide member and provided with a diagonally 30 extending slot, and a lever pivoted adjacent the end of said tubular housing, said lever having a projection extending into said diagonally extending slot whereby transverse swinging movement of said lever will move said slide member 35 longitudinally of said housing.

6. In a loose leaf binder, a tubular housing, an end cap closing one end of said housing, a slide member in said housing, a lever pivoted to said end cap for transverse swinging movement relative to said housing, and a link operable to translate said pivotal movement of said lever into longitudinal movement of said slide member. 40

7. In a loose leaf binder, a tubular housing, an end cap closing one end of said housing, a slide 45 member in said housing, said slide member being provided with a vertical shoulder, and a lever pivoted to said end cap, said lever engaging said shoulder to move said slide member longitudinally of said housing. 50

8. In a loose leaf binder, a tubular housing, an end cap closing one end of said housing, post locking mechanism in said housing, a slide member operable to move said post locking mechanism from locked to open position, a lever operatively connected to said slide member, said lever lying on one side of its dead center position when said post locking mechanism is in locked position and on the other side of said dead center position when said post locking mechanism is 60 in its open position, and a spring having one end secured to said end cap and its other end to said slide member exerting constant force to retain said slide member in either inoperative or operative position. 65

WILLIAM NELSON.
